FIG. 1

FIG. 2

FIG. 1 is a perspective view of a coffee table showing our design, looking down obliquely; and

FIG. 2 is a perspective view of the coffee table of FIG. 1, looking up obliquely.

The coffee table is characterized by the specific features of a non-transparent clover leaf top on a cylindrical base of large diameter, the base being closed at its bottom, and having two diametrically spaced oblong openings in the cylindrical wall of such base.

We claim:

The ornamental design for a coffee table, as shown.
